W. W. WEIR

ELECTRIC HEATER

Filed April 11, 1923

INVENTOR
William W. Weir
BY
White, Frost & Swaine
his ATTORNEYS.

UNITED STATES PATENT OFFICE.

WILLIAM W. WEIR, OF ALAMEDA, CALIFORNIA.

ELECTRIC HEATER.

Application filed April 11, 1923. Serial No. 631,305.

To all whom it may concern:

Be it known that I, WILLIAM W. WEIR,
a citizen of the United States, and a resident
of Alameda, county of Alameda, and State
of California, have invented a certain new
and useful Electric Heater, of which the fol-
lowing is a specification.

The invention relates to electric heaters and particularly to that type of heater known as the "fire place" heater and to portable heaters.

An object of the invention is to provide an electric heater of simple and rugged construction which operates to transmit heat by radiation and convection.

Another object of the invention is to provide a core or support for the heating element which is adapted to cause radiation of the major portion of the heat generated.

20 Another object of the invention is to provide a core having means therein for distributing heat stored therein, by convection.

25 A further object of the invention is to provide an electric heater in which the heating element contacts with its support at small areas only, so that the major portion of the heat is distributed by radiation.

20 The invention possesses other advantageous features, some of which with the foregoing, will be set forth at length in the following description, where I shall outline in full, that form of my invention which I have selected for illustration in the drawings accompanying and forming part of the present specification. In said drawings I have shown one form of heater embodying my invention, but it is to be understood that I do not limit myself to such form, since the invention, as set forth in the claims, may be embodied in a plurality of forms.

Referring to said drawings:—

Figure 1 is a front elevation of a fire place type of heater embodying my invention.

Fig. 2 is a cross section of the heater taken on the line 2—2, Fig. 1.

Fig. 3 is a cross section of the core or tile on which the heating elements are arranged.

Fig. 4 is a detail of the front face of the tile showing a heating coil disposed in a groove therein.

My invention is particularly applicable to the fire place type of electric heater in which the major portion of the heat generated is

distributed by radiation. The heating coils are arranged on the front face of the heater and are so supported that they reach their maximum temperature quickly. This is accomplished by so supporting the heating coils that they contact with the support at spaced points only, these points being of small area so that only a small portion of the heat is transferred to the support by conduction. The heater is therefore effective almost immediately after the circuit is closed. 35

The heater shown in the accompanying drawings comprises a casing 2, of suitable form, the casing, in the present instance, being designed to simulate andirons. The casing is provided with a bottom wall 3, upon which is supported a hollow tile or brick 4 of refractory material. The tile comprises a front wall 5, which is preferably bowed outward, a rear wall 6, which is spaced from the front wall and cross walls 7 connecting the front wall and the rear wall and providing, within the tile, a plurality of vertically extending flues 8, to permit the passage of air through the tile. The heating elements are arranged on the front face of the tile and the heat, which is transferred to the front face by conduction, is transmitted through the walls 7 to the wall 6, thereby providing a large heated surface from which heat is readily transferred to the air column in the flues 8, so that a draft of air is induced through the flues 8. The bottom wall 3 is provided with apertures 9, opening into the flues 8, so that streams of warmed air rise through the flues 8 when the heater is in operation. The tile is provided, on its front face, with a plurality of grooves 12 in which the heating coils 13 are arranged.

These grooves preferably extend horizontally across the front face of the tile and the grooves are inclined downwardly and backwardly, that is, the bottom and top walls 14 and 15 of the grooves are inclined downwardly and backwardly. The groove is narrowed toward its base 16 and the heating coil 13 is of such diameter that, when the coil is disposed in the groove, it contacts with the front wall 14 below the upper edge thereof and with the rear wall 15 above the base thereof and does not contact with the base 16. This results in only a small 95 100 105

area of contact between the heating coil and the tile with the result that only a small portion of the heat is conducted into the tile. The coil is disposed partly below the upper edge of the lower face 14 of the groove, so that the coil is fully supported against sagging and so that, as it expands due to a rise in temperature, it will be still fully supported in the groove. The tile is preferably 10 made of a white clay composition which is highly refractory and which possesses heat reflecting qualities, so that the heat, radiated from the coil against the face of the tile, is reflected outward. The upper wall 15 of the groove acts as a reflector and is so shaped that the major portion of the heat rays, striking such wall, are reflected forwardly.

The tile is arranged in the casing 2, in 20 spaced relation to the rear wall 17 of the casing so that a flue is provided between the rear wall 6 of the tile and the rear wall 17 of the casing and the bottom plate 3 is provided with apertures 18 to permit the entry 25 of air into this flue. The tile is preferably rounded on its upper rear edge to provide a smooth path of egress for the air rising through this flue. The upper portion of the casing is closed by an apertured trimplate 30 19 which extends from the upper forward edge of the tile to the upper edge of the back wall and the hot air rising through the flues in the tile and the flue behind the tile discharges into the room through the apertures 35 in the trim-plate.

A separate heating element, or coil of resistance wire 13, is preferably disposed in each groove and the ends of the coil extend backward through apertures in the tile and 40 are connected on the rear of the tile to bus-bars 21 or other forms of terminals and these terminals are suitably connected to the current supply wires. By making each coil individual and arranging them in parallel, 45 there is substantially no voltage drop between the adjacent points of adjacent coils. Further, should one coil burn out, it may be readily removed and a new coil inserted in its place.

50 I claim:

1. An electric heater comprising a hollow tile of refractory material having vertically disposed passages extending therethrough and a heating element arranged on the front 55 face of the tile.

2. An electric heater comprising a hollow tile of refractory material having vertically disposed passages extending therethrough and having grooves on its front face and 60 heating elements disposed in said grooves.

3. An electric heater comprising a hollow tile of refractory material having vertically disposed passages extending therethrough and having horizontal grooves on its front 65 face and heating elements disposed in the

grooves and lying partly behind the lower walls of the grooves.

4. An electric heater comprising a tile of refractory material having a front wall, a back wall spaced from the front wall and a 70 plurality of walls connecting said front and back walls and forming a plurality of flues extending from the bottom to the top of said tile and electric heating elements disposed on said front wall. 75

5. An electric heater comprising a hollow tile of refractory material having flues extending therethrough, horizontal ridges on the front face of the tile and heating coils disposed on said ridges and partly concealed thereby. 80

6. An electric heater comprising a tile of refractory material, a plurality of horizontal ridges on the front face of the tile and heating coils disposed on said ridges and partly concealed thereby. 85

7. An electric heater comprising a tile of refractory material having grooves across its front face and heating coils disposed in the grooves, the grooves being narrowed toward 90 their bases whereby the heating coils are held from contact with the bases.

8. An electric heater comprising a tile of refractory material having grooves across its front face, the groove extending downwardly and backwardly and being of decreasing height backwardly and heating coils disposed in the grooves and contacting with the top and bottom walls thereof and spaced from the bottoms of said grooves. 100

9. In an electric heater a support of refractory material having a groove in its front face, the upper and lower walls of the groove being inclined downwardly and backwardly and a heating coil disposed in the groove and bearing against the lower wall below the upper edge thereof and contacting with the upper wall above the bottom thereof, the coil being out of contact with the base of the groove. 105

10. In an electric heater, a base, a hollow tile of refractory material disposed on said base and having flues extending therethrough, said base being provided with apertures opening into said flues and heating coils arranged on the front face of said tile. 115

11. In an electric heater, a casing, a back wall on said casing, a hollow tile of refractory material having flues extending therethrough arranged in said casing and spaced from said back wall and heating coils arranged on the front face of said tile. 120

12. In an electric heater, a casing, a back wall on said casing, a hollow tile of refractory material having flues extending therethrough arranged in said casing and spaced from said back wall, heating coils arranged on the front face of said tile and an apertured trim-plate extending between the top 125 of the tile and the top of the back wall. 125

13. In an electric heater, a casing, a back wall on said casing, an apertured bottom wall in said casing, a hollow tile of refractory material having flues extending there-through disposed in said casing and spaced from said back wall, the apertures in the bottom wall opening into said flues and into the space between the tile and the back wall, heating coils arranged on the front face of the tile and an apertured trim-plate closing 10 the top of the casing.
- In testimony whereof, I have hereunto set my hand.

WILLIAM W. WEIR.
